AMOS RANK, OF SALEM, OHIO.

Letters Patent No. 77,525, dated May 5, 1868.

IMPROVEMENT IN HARVESTERS.

The Schedule referred to in these Letters Patent and making part of the same.

TO ALL WHOM IT MAY CONCERN:

Be it known that I, AMOS RANK, of Salem, in the county of Columbiana, and State of Ohio, have invented certain new and useful Improvements in Harvesting-Machinery; and I do hereby declare that the following is a full, clear, and exact description thereof, reference being had to the accompanying drawings, making a part of this specification, in which—

Figure 1, sheet 1, is an elevation of one side of a reaping-machine having my improvements applied to it.

Figure 2, sheet 1, is a plan view of the improved draught-frame, with driving-wheels and driving-gear applied to it.

Figure 3, sheet 1, is a longitudinal section through the main frame, taken in the vertical plane indicated by red line xx in fig. 2.

Figures 4, 5, and 6, show particularly the construction of the draught-frame.

Figures 7 and 8, sheet 2, show my improved pawl-and-ratchet device for raising and lowering the finger-bar, and sustaining it at any desired height from the ground.

Similar letters of reference indicate corresponding parts in the several figures.

The invention relates to a new and improved device, which is designed for adjusting and securing a hinged finger-bar of a harvesting-machine at different heights from the ground, whereby a vibrating hand-lever, combined with a ratchet and a pawl, can be employed, and the lever moved forward or backward, at pleasure, without employing draw-rods, or other devices hitherto used for releasing the pawl from its ratchet-teeth and holding it up, as will be hereinafter described.

To enable others skilled in the art to understand my invention, I will describe its construction and operation.

In the accompanying drawings, fig. 1, I have represented my improvements applied to a machine which is arranged for mowing. By detaching the shoe, A, from its pivoted drag-bar, B, and attaching raking and reeling-devices, with their necessary appurtenances, the machine will be adapted for cutting grain.

The draught-frame, C, which I shall hereinafter describe, is supported upon two transporting-wheels, D D', both of which are applied loosely upon a transverse axle, E, and provided with ratchet or clutch-wheels and dogs, which will engage said driving-wheels with their axle, when the machine is drawn forward. When the machine is backed, the ratchets and dogs allow the wheels to turn loosely around their axle. The axle E has its bearings in boxes upon the bottom sides of the longitudinal bars of the frame C, so that this frame is supported upon said axle. A large bevel-spur wheel, F, is keyed upon the axle E, on one side of the middle of the length thereof, which wheel engages with a pinion-spur wheel, a, upon a short shaft, b, which has its bearings in the front transverse bar of frame C. Pinion-wheel a is placed loosely upon its shaft b, but is caused to turn with it by means of a spring-clutch, a', which has an annular groove in its periphery, that receives a lever, a'', upon the frame-box G. By means of this lever the attendant can engage or disengage clutch a', and stop or start the shaft b at pleasure, while the machine is being drawn forward.

On the front end of the shaft b a large inside spur-wheel, b', is keyed, which is closed in front, and protected by a shield, c, in rear. On the inside of this wheel b', and engaging with its teeth, is a pinion-spur wheel, d, upon a longitudinal shaft, e. This shaft is arranged in a plane below the plane of the longitudinal shaft b, and is supported in bearings formed in the front and rear cross-bars of frame C, as will be further described hereinafter.

On the rear end of shaft e is a balance-wheel or crank-wheel, f, having a wrist-pin applied eccentrically to its rear face, to which the pitman-rod f', which operates the sickle, is suitably attached.

On top of the main frame C, and suitably hinged thereto, at its rear end, is the frame-box G, which has the lever a'' pivoted to it, and which is provided with a driver's seat, G¹, a tool-box, G², and a housing, G³, for the upper part of the large spur-wheel F. This box forms a kind of platform for the driver, upon the open frame C, and also protects the gearing upon this frame. It is held down in place at its front end by a spring-latch, g, which is secured to the shield c in a suitable manner. By detaching the box G from its latch, its front end can be raised and thrown back, which will expose the gearing on frame C.

The finger-bar A' is hinged to the drag-bar B by means of its shoe A, so that the points of the fingers can be adjusted, and any required degree of pitch given to them.

The drag bar B is attached, by a link and swivel-pin, to an arm, h, which projects laterally from the grain-side of the draught-frame C, in front of the transporting-wheel D', as shown in fig. 1; and this drag-bar is again attached to the draught-frame, near its rear end, by means of an inclined transverse brace, h'. Thus it will be seen that the finger-bar is free to rise and fall, and accommodate itself to the undulations of the ground passed over.

Having thus described a harvesting-machine which is especially adapted for my improvements, I will now proceed to describe these improvements, commencing with the draught-frame C. This frame is made of metal; and I prefer to have it made of one piece of metal, so that it will be rigid and substantial, and have no joints to work loose. It consists of two longitudinal bars, connected together at their front and rear ends by means of depressed bars j j', which latter are adapted for supporting the longitudinal shafts b e, above referred to. The laterally-projecting arm h, for the drag-bar attachment, and an elevated support, i, are also constructed upon and constitute a part of the frame C, as shown in the drawings.

The front depressed cross-bar j of frame C is constructed with two separated bearings, k k, having a space between them, so that they afford a wide bearing for sustaining the shaft b at two points. These bearings have half-round channels in their upper surfaces, which, with the caps l l, hold the shaft b firmly, and constitute its journal-boxes. The square-headed bolts are inserted through said journal-boxes from below, and receive nuts upon their upper ends, which can be readily removed at pleasure.

Below these journal-boxes is another journal-box, m, formed by depressing bar j so far below the bearings k k as to allow the cap m' to be introduced into its place and removed at pleasure.

As the longitudinal shaft e has a bearing upon the rear cross-bar j', the front bearing on cross-bar j need not be made as wide as the spaces occupied by the two bearings or boxes of the shaft b; consequently there is left plenty of space in front and in rear of the portion m of bar j for inserting the bolts through the two journal-boxes of shaft b. The cap m' extends partly beneath the boxes of shaft b, and the bolt which secures this portion of the cap to its seat is inserted through the space left between said boxes for this purpose. By thus constructing the bar j, it will be seen that the journal-boxes of shaft b, and the front journal-box of shaft e, are brought in a more compact space than has hitherto been accomplished; and while this is the case, these journal-boxes are very accessible for oiling and other purposes.

The rear shield c, of the inside spur-wheel b', is constructed of a semicircular form, slightly greater in diameter than that of said wheel, so that the flange upon this shield will lap over the spur-wheel, as shown in fig. 3. From the lower edge of the shield c are two projecting pieces, through which the two bolts of the front journal-box of shaft b pass, so that these bolts will serve to secure the shield in place also. In practice, the spring-latch g will be riveted permanently to the shield c.

To the elevated laterally-projecting support i of frame C, the rear end of a longitudinal ratchet-plate, J, is rigidly bolted. Its front end is suitably applied to and supported by a cap or hub on the grain-side of the transporting-wheel D'. To this plate J, and at a point which is concentric to certain ratchet-teeth, p p p, on the upper edge of this plate, a hand-lever, k, is pivoted, so as to vibrate longitudinally, and in a vertical plane. This lever carries a grooved segment, L, to which a rope or chain, s, is attached so as to lie in its groove. This chain is carried back, and passed over a grooved pulley, t, on plate J, and is again attached to the transverse brace h', to the shoe A, or to the drag-bar B, so that by vibrating lever K, the finger-bar and its appurtenances can be raised or depressed.

On the inner side of lever K, a pawl or dog, O, is pivoted, so as to engage with the teeth p, and when engaged therewith, to prevent lever K from moving forward. The pawl O may be made like any well-known pawl which is used with a ratchet. My object now is to so construct the ratchet or catch-plate that lever K can be vibrated forward or backward at pleasure, and the pawl O made to catch at any desired point where there is a ratchet-tooth. With the well-known pawl and ratchet, it is necessary to lift the pawl, and disengage it from the ratchet-teeth when it is desired to adjust the pawl forward, or in a direction opposite to the pitch of the teeth; and contrivances have been employed, in connection with pawls upon long adjusting-levers, for this purpose. My improvement consists in having notches or spaces v v, between the ratchet-teeth, of such depth as will allow the pawl O to drop into them, and turn back when the lever K is moved forward for the purpose of lowering the finger-bar, as shown in figs. 7 and 8, sheet 2. Under this arrangement, if it is desired to adjust the pawl O forward one tooth or notch, the lever K must be moved back until the pawl falls into one of the spaces v. Then the lever must be moved forward until the pawl drops into one of the spaces v forward of the intended tooth or notch, when lever K can then be moved back, and its pawl made to catch at the point desired. The spaces v may be made at intervals of one, two, or more teeth of the ratchet, if desired.

Having described my invention, what I claim as new, and desire to secure by Letters Patent, is—

In combination with a vibrating lifting-lever, K, and its pawl O, I claim the construction of the ratchet-plate J, with spaces v between the teeth p thereof, substantially as described.

AMOS RANK.
